UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE

REFRIGERATING APPARATUS

Application filed February 6, 1928. Serial No. 88,591.

This invention relates to cooling units for mechanical refrigerators. An object of this invention is to provide a simple and efficient form of cooling unit having a large longitudinal dimension compared to its transverse dimensions whereby said unit may be conveniently located within a long relatively narrow space. This type of cooling unit is adapted for use in the conventional form of display cases found in restaurants, lunch rooms, delicatessens, etc., which have a long narrow compartment extending longitudinally of the case and wherein cracked ice is ordinarily kept for maintaining the case at a lower temperature. The cooling unit of this invention is designed to fit within such long narrow compartments by extending the cooling tubes only in the same direction with the long dimension of the header tank to which the tubes are connected and which serves as a liquid refrigerant reservoir for said tubes.

Further objects and advantages of the present invention will be apparent from the following description, reference being had to the accompanying drawings, wherein a preferred form of embodiment of the present invention is clearly shown.

In the drawings: Fig. 1 shows an end view of a form of display case having a part of the end wall broken away showing the front end view of a cooling unit built according to this invention located therein.

Fig. 2 is a side elevation of the cooling unit. Fig. 3 is a plan view of the cooling unit. Fig. 4 is a rear end elevation of the cooling unit.

Similar reference characters refer to similar parts throughout the several views.

Numeral 10 designates the cylindrical header or tank which is provided with a front cover plate 11 which is rigidly held to the flange 12 of cylinder 10 by the cap screws 13. Liquid refrigerant is led to tank 10 through the pipe connection 15 and the vaporized refrigerant is led from the tank through the upper pipe connection 16. A suitable type of float valve 17 is contained within the tank 10 to maintain the liquid level therein con-

stant at some point below the vapor outlet 18. Long slender heat transfer tubes are arranged compactly in different planes and form what may be termed a spike-like portion of the evaporator. These tubes are connected at their outer ends to form hairpin shaped loops 20 which are individually connected to the header tank 10 in parallel relation and project rearwardly therefrom, as clearly shown in the drawings, any desired distance in order to extend substantially the full length of the display case or other long compartment cooled thereby. The lower connection 21 of the loops 20 to the tank 10 are staggered as clearly shown in Figs. 2 and 3. The loops 20 are preferably all bent up to substantially the same shape before assembling to the tank 10 for purposes of economy in manufacture. Therefore the staggering of the connections 21 gives a corresponding variation in the lengths of the loops, as clearly shown in Figs. 2 and 3. The upper connections 22 of the loops 20 are made in the rear head 23 of the tank 10 and thus no bends on this end of the tubes is required in order to make the proper connections to the tank 10. The connections 22 are also staggered as clearly shown in Figs. 2 and 4, in order that proper spacing may be obtained. The loops 20 are preferably spread apart slightly at their rear end in order to obtain greater spacing and hence better heat transfer with the medium cooled thereby. The loops 20 are held rigidly in their spaced position by the transverse bands 25 which are soldered firmly to the tubes. The loops 20 are preferably made from seamless copper tubing and have great rigidity when bound together by the bands 25. Hence, this elongated cooling unit may be conveniently inserted and supported within a similar shaped compartment.

It is apparent from the disclosure that vaporization or boiling takes place in both the upper and lower legs of tubes 20 and it is also apparent that should the tubes be flattened or pinched accidentally or on purpose, as is often the case, boiling will still take place on both sides of the flattened portion

and the loop will function as two separate tubes.

Fig. 1 shows an end view of an elongated brine tank 30 which extends the full length 5 of the display case 31, the brine tank 30 being so positioned and of such dimensions that it does not materially detract from the appearances of the glass walled display case. The cooling unit shown in Figs. 2, 3 and 4

10 is suitably supported within the brine tank 30 and maintains the brine at the desired temperature. The air within the display case 31 circulates around the outside of the brine tank 30 and is cooled thereby.

15 While the form of embodiment of the present invention as herein disclosed, constitutes a preferred form, it is to be understood that other forms might be adopted, all coming within the scope of the claims which follow.

20 What is claimed is as follows:

1. A cooling unit for mechanical refrigerators comprising: an elongated header tank adapted to contain liquid refrigerant at a substantially constant level, a plurality of 25 duct loops each having a plurality of legs connected to said header, one of said legs being connected to one end wall of said tank and projecting a substantial distance in the longitudinal direction of said tank.

30 2. A cooling unit for mechanical refrigerators comprising: an elongated header tank adapted to contain liquid refrigerant at a substantially constant level, a plurality of duct loops connected in parallel to said header, said loops each having one leg connected to one end wall of said tank and projecting a substantial distance in the longitudinal direction of said tank, and a second leg lying relatively close to said first leg and connected to a lateral wall of said tank.

35 3. A cooling unit for mechanical refrigerators comprising: an elongated header tank adapted to contain liquid refrigerant at a substantially constant level, a plurality of 45 duct loops each having the ends thereof connected to said header, said loops being so shaped and disposed relative to one another and to the tank that they form a horizontally elongated group having transverse 50 dimensions approximating those of said tank.

40 4. A cooling unit for mechanical refrigerators comprising: an elongated header tank adapted to contain liquid refrigerant at a substantially constant level, a plurality of 55 duct loops connected in parallel to said header, said loops each having one leg connected to one end wall of said tank and projecting a substantial distance in the longitudinal direction of said tank, and a second 60 leg lying relatively close to said first leg and connected to a lateral wall of said tank, and means for rigidly holding said loops in spaced relation and thereby forming a substantially rigid construction.

65 5. A cooling unit for mechanical refriger-

ators comprising: an elongated and horizontally disposed header containing a quantity of volatile liquid refrigerating medium, a plurality of ducts connected with the header for circulating the refrigerating medium, said ducts being connected to one end wall of said header and projecting a substantial distance in the longitudinal direction of said header.

70 6. A cooling unit for mechanical refrigerators comprising: an elongated header containing a quantity of volatile liquid refrigerating medium, a plurality of ducts connected with the header for circulating the refrigerating medium, portions of said ducts being connected to one end wall of said header and other portions being connected to a lateral wall of said header and projecting a substantial distance in the longitudinal direction of said header.

75 7. A cooling unit for mechanical refrigerators comprising: a header containing a quantity of volatile liquid refrigerating medium, a plurality of duct loops connected with the header for circulating refrigerant medium, said loops being so shaped and disposed relative to one another and to the header that they form a horizontally elongated group having transverse dimensions approximating those of said header.

80 8. A cooling unit for mechanical refrigerators comprising: an elongated and horizontally disposed tank containing a quantity of volatile liquid refrigerating medium, conduit means connected with the tank for circulating the refrigerating medium, said means being connected to one end wall of said tank and projecting a substantial distance in the longitudinal direction of said tank.

85 9. A cooling unit for mechanical refrigerators comprising: an elongated and horizontally disposed tank containing a quantity of volatile liquid refrigerating medium, conduit means connected with the tank for circulating the refrigerating medium, a portion 100 of said means being connected in one end wall of the tank and another portion being connected to a lateral wall of said tank, said portions projecting a substantial distance in the longitudinal direction of said tank.

10. In combination, an elongated brine tank and a cooling unit for cooling the brine, said cooling unit comprising an elongated header containing a quantity of volatile liquid refrigerating medium and disposed within and adjacent one end of the brine tank, a plurality of ducts connected with the header for circulating the refrigerating medium, said ducts being connected to one end wall of said header and projecting a substantial distance in the longitudinal direction of said header and toward the other end of said brine tank.

11. In combination, an elongated brine tank and a cooling unit for cooling the brine,

said cooling unit comprising an elongated header containing a quantity of volatile liquid refrigerating medium and disposed within and adjacent one end of the brine tank, a plurality of ducts connected with the header for circulating the refrigerating medium, portions of said ducts being connected to one end wall of said header and other portions being connected to a lateral wall of said header and toward the other end of said brine tank.

12. A horizontally elongated evaporator unit having a spike-like portion comprising a compact group of long slender horizontally disposed tubes arranged in different horizontal and different vertical planes and forming the greater part of the horizontal length of the unit, means forming a fluid connection between the tubes including a header, said header having an inlet for liquid refrigerant and an outlet for gaseous refrigerant, and means for controlling the liquid refrigerant level within the header.

13. A horizontally elongated evaporator unit having a spike-like portion comprising a compact group of long slender horizontally disposed tubes arranged in different horizontal and different vertical planes and forming the greater part of the horizontal length of the unit, means forming a fluid connection between the outer ends of the tubes, a header connecting the inner ends of the tubes, and means for controlling the refrigerant level within the header.

14. A horizontally elongated evaporator unit having a spike-like portion comprising a compact horizontal group of long slender tubes forming the greater part of the horizontal length of the unit, said tubes provide a plurality of hair pin shaped loops, a header connecting the ends of the loops, and means for controlling the refrigerant level within the header.

15. An evaporator for mechanical refrigerators comprising a cylindrical header containing a quantity of volatile refrigerant, a compact horizontal group of long slender tubes forming the greater length of the evaporator, certain of said tubes being connected with the cylindrical wall of the header and certain of said tubes being connected with an end wall of the header.

16. An evaporator for mechanical refrigerators comprising a cylindrical header containing a quantity of volatile refrigerant, a compact horizontal group of long slender tubes forming the greater length of the evaporator, said tubes providing a plurality of hair-pin shaped loops, one end of a tube being connected with the cylindrical wall of the header and the other end of the tube being connected with an end wall of the header.

17. An evaporator for mechanical refrigerators comprising a cylindrical header containing a quantity of volatile refrigerant, a

compact group of long slender horizontally disposed tubes arranged in different horizontal and different vertical planes and forming the greater length of the evaporator, said tubes providing at least one circuit for refrigerant having the ends thereof connected with the cylindrical wall and an end wall of the header respectively. 70

18. An evaporator for mechanical refrigerators comprising a cylindrical header containing a volatile liquid refrigerant, a compact group of slender tubes having long horizontal runs arranged in different horizontal and vertical planes, said tubes being connected with the header and forming a plurality of horizontally disposed hair-pin shaped loops, one end of a tube being connected with the cylindrical wall of the header and the other end of the tube being connected with an end wall of the header. 75 80 85

19. An evaporator for mechanical refrigerators comprising a cylindrical header containing a volatile liquid refrigerant, a compact group of slender tubes having long horizontal runs arranged in different horizontal and vertical planes, said tubes being connected with the header, certain of said tubes being connected with the cylindrical wall of the header and certain of said tubes being connected with an end wall of the header, the 90 95 opposite end wall of the header having a liquid refrigerant inlet and a gaseous refrigerant outlet, and means responsive to the quantity of liquid refrigerant in the header for controlling the flow of refrigerant 100 through said inlet.

20. An evaporator for mechanical refrigerators comprising a cylindrical header containing a volatile liquid refrigerant, a compact group of slender tubes having long horizontal runs arranged in different horizontal and vertical planes, said tubes forming at least one circuit for refrigerant having the ends thereof connected with the cylindrical wall and an end wall of the header respectively. 105 110

In testimony whereof I hereto affix my signature.
